UNITED STATES PATENT OFFICE

JACOB S. BROWN, OF COMPTON, CALIFORNIA, ASSIGNOR OF ONE-HALF TO HARRY C. BROWN AND ONE-HALF TO E. A. WILEY, BOTH OF COMPTON, CALIFORNIA

UNDERREAMING WELL-DRILLING BIT

Application filed November 14, 1927. Serial No. 233,137.

My invention is a well drilling bit of the rotary type to ream a hole larger than that through which the bit is inserted.

An object of my invention is the construction of a bit with cutting jaws or teeth which may be slid radially outwardly to increase the diameter of the bit, and therefore ream a hole of larger diameter than that through which the bit is inserted.

10 A further object of my invention is in causing the sliding movement of the jaws by a partial rotary motion of the drill rod.

Another object of my invention is in utilizing a pin and slot connection between the 15 slideable jaws and a rotatable element connected to the drill rods to thrust the teeth outwardly, but I do not rely on the pins to form a driving connection for the jaws, this driving connection being by means of interengaging lugs on the foot of the bit, in which 20 the jaws are slideable, and a rotary element connected to the drill rods.

In constructing my invention I utilize a shank which is connected to the lower end of 25 a string of tubular drill rods. This shank at its lower end has pins, preferably three, and it has a threaded section in which sleeves are threaded and locked by set screws, the lower sleeve having depending arcuate lugs. Outside of these sleeves and rotatably mounted 30 thereon there is a collar which fits over a cylindrical section of the shank; and internally connected to the collar by a screw-threaded connection there is the foot of the bit. This 35 foot has arcuate lugs to engage with the lugs on the lower sleeve. The foot has radial slots for the jaws and these jaws each have a slot which engages with one of the pins on the lower end of the shank.

40 After the bit has been introduced in the well in a collapsed position, the drill rods are given a turn in the same direction of rotation as when reaming, then the jaws are forced outwardly by the relative partial turning 45 movement of the shank and the foot and col-

lar, and if desired the initial movement of the jaws may be aided by the flushing liquid being pumped through the tubular drill rods and the shank into the center of the foot.

When the jaws engage the formation and the reaming starts, they are forcibly thrust outwardly to their full extent and held in this position, but the driving is not through the pins but through the interconnecting arcuate lugs on the lower sleeve and the upper 50 part of the foot.

My invention will be more readily understood from the following description and drawings, in which:

Figure 1 is a perspective view of a well hole 60 with my bit introduced therein.

Fig. 2 is an elevation of the shank, showing the lower parts of the bit in partial vertical section.

Fig. 3 is an elevation of the bit.

Fig. 4 is a horizontal section on the line 4—4 of Fig. 2 in the direction of the arrows.

Fig. 5 is a horizontal section on the line 5—5 of Fig. 2 in the direction of the arrows. These figures show the jaws in their collapsed 70 position.

Fig. 6 is a view similar to Fig. 5, showing the driving connection between the sleeve on the shank and the foot through the interengaging arcuate lugs.

Fig. 7 is a view similar to Fig. 4 with the jaws extended.

Fig. 8 is a bottom view of a bit, taken in the direction of the arrow 8 of Fig. 1.

Fig. 9 is a perspective of the shank with 80 the sleeves thereon.

Fig. 10 is a perspective view of the foot looking in the direction of the arrow 10 of Fig. 11.

Fig. 11 is a perspective view of the foot 85 looking in the direction of the arrow 11 of Fig. 10.

Fig. 12 is a vertical cross section through the collar.

Fig. 13 is a side elevation of one of the jaws 90

taken in the direction of the arrow 13 of Fig. 14.

Fig. 14 is a back edge view taken in the direction of the arrow 14 of Fig. 13.

Fig. 15 is a front edge view taken in the direction of the arrow 15 of Fig. 13.

Fig. 16 is a top view taken in the direction of the arrow 16 of Fig. 13.

In my invention I utilize a cylindrical tubular shank 11 having a pin 12 at the upper end which is adapted to engage in a box 13 on the lower end of a string of tubular drill rods 14, the shank having the usual shoulder 15 at the top. The shank has a reduced lower end having a cylindrical section 16 and a screw-threaded section 17 with a shoulder 18 above the screw-threaded section (Fig. 2). There are also a series of pins 19 on the base or lower end of the shank, and the shank has a central flushing duct 20 (Figs. 2 and 9). Threaded on the threaded section of the shank there is an upper sleeve 21 which fits against the shoulder 18 and a lower sleeve 22, this latter sleeve being locked in position by a set screw 23. This lower sleeve has a pair of arcuate lugs 24 (Figs. 2 and 9).

Mounted on the shank for partial rotation there is a collar 25 which has an annular groove 26 at the top with packing 27 therein. The lower end of the sleeve is internally threaded at 28. An antifriction bearing 29 is positioned between the upper sleeve 21 and a shoulder 30 at the upper part of the collar (Figs. 2 and 12). A foot 31 (shown in detail in Figs. 2, 10 and 11) has an upper reduced threaded end 32 which engages the internal threads 28 of the collar and on the upper edge this foot is provided with a pair of arcuate lugs 33 which are adapted to interengage with the lugs 24 on the lower sleeve 22. The lower end of the collar abuts against a shoulder 35 on the foot.

The foot has radial guide-ways designated generally by the numeral 36, there being three illustrated, and each guide-way has a vertical wall 37 at one side, a vertical wall 38 on the other side, this latter wall having a radial recess 39 (note Figs. 3, 5, 7, 8, 10 and 11). At the inner end of the side wall 37 there is a vertical shoulder 40, and set out therefrom there is a parallel shoulder 41. These shoulders together with the surface 38 of the next adjacent radial guide-way 36 form a vertical tongue 42.

The construction of the jaws is substantially as follows, each jaw being designated generally by the numeral 43, and being illustrated particularly in Figs. 5, 7, 8 and 13 through 16: Each jaw has a substantially vertical cutting edge 44 with a curved section 45 forming a clearance and a rear vertical outer corner 46. The lower part of the vertical edge 44 is curved outwardly, as indicated at 47, and joins the bottom forward edge 48 at a point 49. The upper portion of the

back 50 is vertical and each jaw has a flat top 51 in which there is a groove 52 cut in from the back, and a lug 53 extends outwardly from the front face 54. This latter face preferably has an angularly cutaway section 55 ending in a vertical edge 56.

When assembled in the foot, each of the jaws has its lug 53 sliding in the recess 39, which prevents the jaws from dropping out vertically, and one of the pins 19 fits in each of the slots 52. When the jaws are in their innermost position the edge surface 56 abuts against the vertical shoulder 40 of the foot and leaves a radial space 57 between the surface 56 and the vertical shoulder 41. Also when the jaws are thrust in to the full extent, there is a somewhat triangular space 58 left in the center, due to the cutaway sides 55 (see Fig. 5).

The manner of operation and functioning of my bit is substantially as follows:

The bit is introduced into a well through a well casing, as indicated in Fig. 1, which casing is shown as cementing off the upper part of the well. When the cutting jaws are below the bottom of the casing the drill rod is given a rotation, preferably in a right-handed direction of Figs. 5 and 7; and at the same time the flushing liquid is forced down through the tubular drill rods, and discharges into the triangular space 58 formed by the jaws in the foot. This flushing fluid, on account of the radial space 57, exerts a pressure on the inner ends 56 of the jaws, tending to force such jaws outwardly, and moreover, there is usually a certain friction which tends to retard the rotary motion of the foot 31 and of the collar 25.

Therefore, in this turning motion the pins 19 shift from the position shown in Fig. 5 to that of Fig. 7 in reference to the slots 52 in the jaws and force the jaws outwardly from the housed position of Fig. 5 to the extended position of Fig. 7. When the jaws are in this position, the arcuate lugs 24 on the lower sleeve 22 engage the arcuate lugs 33 on the upper part of the foot so that the driving force is transmitted from the shank through the sleeve 22, the arcuate lugs 24, to the arcuate lugs 33 of the foot 31 and hence the jaws are driven in a rotary motion by the foot and in the extended position.

It will therefore be seen that none of the driving force is transmitted through the pin and slot connection 19 and 52, but all this driving force is taken by heavy and substantial parts. In the slight rotary motion the balls 29 facilitate this partial turn.

It will therefore be seen from the above description, together with the drawings, that I have developed a simple type of under reamer bit in which the jaws are slid directly radially outwardly, and this action takes place through a partial rotary motion of the drill rod in the same direction as this rod is

turned in the reaming operation; and also after the jaws are forced outwardly, they are rotated, through the medium of the foot which is a substantial body, in their cutting and reaming work. This foot is driven by heavy and substantial arcuate lugs, the driving force being transmitted through the shank 11.

Various changes may be made in the principles of my invention without departing from the spirit thereof, as set forth in the description, drawings and claims.

I claim:

1. A drill bit having in combination a tongue transmitting shank, a foot mounted thereon for partial relative rotational movement, said foot having a plurality of guide-ways extending towards the center, a jaw slidably mounted in each guide-way, there being a pin and slot connection between each of the jaws and the shank, said pin and slot connection forcing the jaws outwardly on partial rotational movement of the shank relative to the foot, a driving means comprising arcuate lugs on the foot, a sleeve rigidly connected to the shank having arcuate lugs, the said lugs engaging on the extension of the said jaws.

2. A drill bit having in combination a shank, a sleeve fixedly secured thereto having arcuate lugs, a collar mounted on the shank extending over the sleeve, a foot connected to the collar and having arcuate lugs to engage the lugs on the sleeve, the foot having radial guide-ways, a jaw slidably mounted in each guide-way, and a pin and slot connection between the shank and each of the jaws to force said jaws outwardly on partial rotation of the shank relative to the foot, said rotation interengaging the lugs, said latter forming a driving means to drive the foot from the shank and hence the jaws.

3. A drill bit having in combination a tubular shank, a foot mounted thereon for limited rotational movement, said foot having a plurality of radial guide-ways, a jaw slidably mounted in each guide-way, a pin and slot connection between the shank and each of the jaws, said jaws when contracted leaving an open space for the entrance of flushing fluid through the tubular shank, a pin and slot connection forcing the jaws outwardly on partial rotation of the shank relative to the foot, and the flushing fluid being adapted to aid in the initial movement.

4. A drill bit comprising in combination a tubular shank having a sleeve connected thereto, arcuate lugs on the sleeve, a collar rotatably mounted on the shank and extending over the sleeve, a foot connected to the collar and having arcuate lugs to engage the lugs of the sleeve, said foot having radial guide-ways, a jaw slidably mounted in each guide-way and having a pin and slot connection to the shank, said jaws when con-

tracted leaving an open space for the entrance of flushing fluid passing through the tubular shank, said pin and slot connections extending the jaws on partial rotation of the shank relative to the foot, the initial movement being adapted to be aided by the flushing fluid bearing on the inner edges of the jaws, and the said lugs forming a driving connection when the jaws are extended.

In testimony whereof I have signed my name to this specification.

JACOB S. BROWN.
